UNITED STATES PATENT OFFICE.

EDWARD Y. MOORE, OF CHICAGO, ILLINOIS.

CAR-DOOR.

SPECIFICATION forming part of Letters Patent No. 334,452, dated January 19, 1886.

Application filed April 6, 1885. Serial No. 161,347. (No model.)

To all whom it may concern:

Be it known that I, EDWARD Y. MOORE, residing at Chicago, in the county of Cook and State of Illinois, have invented certain new and useful Improvements in Car-Doors, of which the following, in connection with the accompanying drawings, is a specification.

In the drawings, Figure 1 is a side elevation showing the outer side of a grain-car door in connection with my improvements and so much of the car as is necessary in order to illustrate my invention. Fig. 2 is a side view of so much of the interior of the car as is necessary to illustrate my invention. Fig. 3 is a section in the plane of the line $\alpha\alpha$ of Fig. 2, viewed in the direction indicated by the arrow there shown. Fig. 4 is a like representation representing the part shown in Fig. 3, showing the door locked in its raised position. Fig. 5 is a detail, the same being a side view of one of the locking-buttons and the plate to which it is attached. Fig. 6 is a detail, the same being an edge view of one of the locking devices; and Fig. 7 is a side view, in detail, of the means employed for locking the door temporarily in its raised position.

Like letters of reference indicate like parts.

A represents the side of the car. B is the main grain-door, and B' is a supplemental grain-door, hinged to the door B by means of hinges $a a$. The door B' is only a minor feature of my invention, and may be employed with advantage when the car is loaded with oats or with the lighter kinds of grain, but is not necessary when carrying wheat or corn. The door B', as will be perceived, is arranged upon the upper edge of the door B, and folds inwardly, but is retained temporarily in its vertical position, or upon the edge of the door B, by means of a pivoted button, b , applied, by preference, to the door B'.

C is a forked or notched plate applied to the door B', and its forked arms are bent inward at or near their ends, as shown at $c c'$.

D is a plate applied to the door B.

E is a small screw-bolt in loose connection at one end with the plate D or the door B, and d is a flanged or winged thumb-nut run upon the other end of the bolt E.

To hold the door B' down or in against the inner side of the door B, I raise the button b ,

and then turn the door B' down, and thus bring the arms of the forked plate C just over the bolt E. I then raise the said bolt up between the said arms and tighten the said nut. 55 The upper or supplemental door will thus be firmly secured against the inner side of the lower or main door.

F are metallic eyes applied to the inner side of the door B, somewhat below its upper corners, and G G are metallic boxes or bearings applied to the door-frame.

H H are connecting rods or links, bent at their upper ends to enter or be journaled in the boxes or bearings G G, and ee are comparatively long loops at the other ends of the said links. These loops are linked into the eyes F F. The upper portion of the links H H are curved, as shown at $e'e'$. By these means the door B may be raised and lowered, 65 whether provided with a door, B', or not. The extent to which it may be raised or lowered depends upon the length of the loops ee , and I make these loops sufficiently long to 70 allow the door to be raised high enough to 75 permit the grain to pass out freely underneath it when occasion requires. Also, by employing the looped links H H, the door may be folded compactly up against the roof of the car, as represented in Fig. 4, and when the 80 door is in this position one edge abuts against the side of the car, as will be perceived. I retain the other edge of the door in its raised position temporarily by means which I will now describe.

I is a plate rigidly secured to one of the car-lines, and J is a pendent hook pivoted to the said plate, and having thereon a shoulder or projection, f .

K is an arm or locker pivoted to the plate 90 I, and K' is a fixed stud or pin extending from the said plate, for limiting the upward movement of the part K.

L is a stud or pin, also projecting from the plate I, limiting the swinging movement in 95 one direction of the hook J. The natural position of the hook J is vertical, with one edge in or nearly in contact with the stud L. The hook J is locked in this position by means of the pivoted arm or locker K when the latter 100 rests on the shoulder f , as is clearly indicated in Figs. 4 and 7. The hook J, however, may

be released by raising the locker K sufficiently for that purpose—for example, to the position indicated by the dotted or broken lines in Fig. 7—at which time the pin K' prevents the further upward movement of the locker, and the position of this pin is such that the locker, when released, will fall back upon the shoulder f.

To lock the door temporarily in its raised position, I raise the locker K, while raising the door against the roof, and as the door passes up its edge strikes the beveled end of the hook J and throws the latter back out of the way. As soon, however, as the door is in its fully-raised position, the hook J falls to its vertical position and engages the door, so as to hold the latter up. To lock the hook in its engaging position, I release the locker K.

M is a plate secured to or set into the sides 20 of the door-frame, and this plate has in it a depression, g, and a hole or opening, h.

N is a pivoted latch or button applied to the plate M, and adapted and arranged for being swung or vibrated, so as to alternately 25 cover and expose the depression g.

O is a plate secured to the outside of the door B, and O' is a leaf hinged thereto.

O" is a stud or pin projecting from one side 30 of the leaf O', and the outer end of this stud is beveled, as is clearly shown in Fig. 6.

To lock the door in its closed position, I turn the leaf O' over into the depression g, when the stud or projection O" will enter the hole or opening h. The wing O' will then be flush 35 or nearly flush with the outer plate, M. Now, by swinging the button N down over the leaf O', the latter will be locked temporarily in engagement with the plate M; but by swinging the latch or button N away laterally, as shown 40 in Fig. 5, the leaf O' may be released or thrown back, as indicated in Fig. 6. By these means the door will not only be locked in its lowest or closed position, but will also be prevented from being moved or jarred laterally or end- 45 wise. Cleats P P may also be placed upon the outer side of the door at its ends, to further aid in retaining the closed door in its proper position firmly.

Q is a lift-plate applied to the outer side of 50 the door; but such a plate is not new with me.

It will be perceived from the foregoing description, and on reference to the drawings, that the looped links or rods H H not only permit the door to be raised vertically from 55 the outside of the car, to allow grain to pass out underneath it, but that they also allow the door, whether it consists in part of the supplemental door or not, to be turned closely against the roof, and that there are then no 60 projecting parts extending into the car in such a manner as to interfere with the storage of lumber or other merchandise. This feature of my invention I believe to be new, independently of the supplemental door and of 65 any specific features of construction relating to the means employed for locking the door either in its closed or open position. Fur-

thermore, when the door is raised to the roof, the links H H aid in supporting it there. The hook J and keeper or locker K hold the door firmly in its raised position and co-operate with the looped links to this extent—viz., that the loops allow the door to abut at one edge against the side of the car, while the supporting-hook and the locker retain the door 70 temporarily in that position rigidly, and prevent it from being shaken out of place by the movements of the car. The catch or fastening N, in co-operation with the wing O' on the plate O and the stud O", when arranged, as 75 shown, about one-third the way down from the top of the door B, not only serves to hold the door down, but also firmly against the side of the car, both at the top and bottom of the door, thus serving the purpose of catches both 80 at the top and bottom of the latter, and also prevents the door from being moved endwise; but to more effectually prevent the door from being moved endwise I deem it preferable to employ the cleats P P, which slightly overlap 85 the door-posts when the door is closed. The supplemental door B', as before stated, need not be raised upon the edge of the door B, excepting when the car is loaded with light grain, or with a load filling the car sufficiently 90 to render a high door necessary. The button b, operating in conjunction with the hinges a a, serves to hold the door B' firmly in its vertical position, and the means employed for fastening the door B' in its folded position 95 against the door B retain the door B' firmly in that position. The links H H are, by preference, so bent or hinged at their upper ends as to prevent them from being swung or tilted laterally, and this result I accomplish by bending them rectangularly near their upper ends, 100 as shown, and the short horizontal arms so made enter the boxes or bearings G G.

Having thus described my invention, what I claim as new, and desire to secure by Letters 105 Patent, is—

1. The combination, substantially as specified, with a freight-car grain-door, of upwardly-swinging links, each having a long loop on its lower end, and there hinged or jointed to 110 the door, and hinged or jointed at their other ends to the car, for the purposes set forth.

2. The combination, substantially as specified, with a freight-car grain-door, of the upwardly-swinging links H H, each having a 115 loop, e, on its lower end, and there hinged or jointed to the door, and hinged or jointed at their other ends to the car, and of a fastening or support for retaining the door temporarily in its fully open or upturned position, for the 120 purposes set forth.

3. The combination, substantially as specified, of a freight-car grain-door, the upwardly-swinging links H H, each having a loop, e, 125 on its lower end, and there hinged or jointed to the door, and hinged or jointed at their other ends to the car, a pivoted hook arranged for engaging the fully open or upturned door, and a pivoted locker for holding the said hook.

in temporary engagement with the door, for the purposes set forth.

4. A grain-car door consisting of the combination of a main part, B, and of a supplemental part, B', hinged or jointed thereto, substantially as and for the purposes specified.

5. The combination, substantially as specified, of the main inwardly-folding grain-car door B, the inwardly-folding supplemental door B', hinged to the upper part of the door B, a fastening for securing the door B' temporarily in a vertical position on the upper edge of the door B, and a locking device for retaining the door B' temporarily in its position when folded against the door B, for the purposes set forth.

6. The combination, substantially as specified, of the main inwardly-folding grain-car door B, the inwardly-folding supplemental door B', hinged to the upper part of the door B, the pivoted button b, for retaining the door B' temporarily in its vertical position on the upper edge of the door B, and a locking device for retaining the door B' temporarily in its position when folded against the door B, for the purposes set forth.

7. The combination, substantially as specified, in a grain-car door, of the main door B, having thereon the bolt E and nut d, and the

supplemental door B', hinged to the door B, and having thereon the forked plate c, for the purposes set forth.

8. The combination, substantially as specified, with a freight-car and a grain-door in connection therewith, of the pivoted latch N, the plate O, the hinged leaf O', having thereon the stud O'', and an opening to receive the said stud, for the purposes set forth.

9. The combination, substantially as specified, with a freight-car and a grain-door in connection therewith, of the plate M, having therein a recess or depression, g, and an opening, h, the pivoted latch N, the plate O, and the hinged leaf O', having thereon the stud O'', for the purposes set forth.

10. The combination, with an inwardly and upwardly folding grain-car door, of the pivoted pendent hook J, applied to the car-roof, the pivoted gravitating locker K, and a shoulder or support, f, for the said locker, substantially as and for the purposes specified.

In testimony that I claim the foregoing as my own I hereto affix my signature in presence of two witnesses.

EDWARD Y. MOORE.
